UNITED STATES PATENT OFFICE.

FRED WEINBERG, OF SCHENECTADY, NEW YORK.

DETECTOR.

Application filed August 11, 1923. Serial No. 656,809.

To all whom it may concern:

Be it known that I, FRED WEINBERG, a citizen of the United States, residing at Schenectady, in the county of Schenectady 5 and State of New York, have invented new and useful Improvements in Detectors, of which the following is a specification.

This invention has reference to wireless telegraph and telephony and has particular reference to crystal detectors for receiving apparatus.

An object of the present invention is the provision of a combination detector constructed for use with the usual contact wire and mineral, or with two contacting minerals, so that the detector may be easily and quickly changed from one form to the other.

With the above and other objects in view, 20 the invention further includes the following novel features and details of construction, to be hereinafter more fully described, illustrated in the accompanying drawings and pointed out in the appended claims.

25 In the drawings:—

Figure 1 is an elevation of the invention showing a detector arranged for use with two minerals.

Figure 2 is a plan view of the same.

30 Figure 3 is a vertical transverse sectional view.

Figure 4 is an elevation showing the detector arranged for use with one mineral.

Referring in detail to the drawings, 35 wherein like characters of reference denote corresponding parts, the reference character 10 indicates a base which is made from suitable insulating material and which has mounted thereon a cup or receptacle 11 which is adapted to hold a crystal of any 40 suitable character, such as tellurium, galena, pyrites, silicon or the like, as indicated at 12, and which may be held in place by set screws 13. The receptacle 11 is formed 45 of metal and is longitudinally connected to a binding post 14 by means of a conductor wire 15.

Secured to the base 10 by screws 16 is an 50 arch-shaped guide 17, the said guide being electrically connected to a binding post 18 by means of a conductor wire 19.

The guide 17 is provided with an opening 55 for the passage of a hollow arm 20, whose outer end is provided with an insulated finger piece 21. Extending from the opposite inner end of the arm is a contact

wire 22 which is movable longitudinally within the arm and which is yieldingly pressed outward as indicated at 23, so that its outer end may be positioned in contact 60 with the crystal 12 in the usual manner.

The inner end of the arm 20 is externally threaded and is provided with a collar 24 at the inner end of the threads. The arm 20 is further surrounded by a spring 25 65 having one end positioned against the collar 24 and its opposite end positioned against a washer 26 which is movable longitudinally of the arm. This spring provides means for yieldingly forcing the inner 70 end of the arm in a direction toward the crystal. Threadedly engaged upon the inner end of the arm 20 is a receptacle 27, which is adapted to hold a crystal 28 of suitable character. This crystal is designed 75 for contact with the crystal 12 so as to provide a detector which includes contacting crystals. A partition 29 is provided in the receptacle 27 and when the receptacle is in use, the outer end of the contact wire will 80 contact this partition and will force the said contact wire upward into the arm 20. The crystal 28 may thus serve the purpose of the ordinary contact wire. Crystals of 85 any suitable character may be utilized, such as zincite for the receptacle 26 and tellurium for the crystal 12.

It will be apparent from the foregoing description and accompanying drawings, 90 that the detector may be used with a single crystal and contact wire, or the latter may be eliminated without the necessity of its removal and the detector used with two contacting crystals.

The invention is susceptible of various 95 changes in its form, proportions and minor details of construction and the right is herein reserved to make such changes as properly fall within the scope of the appended 100 claims.

Having described the invention what is claimed is:—

1. In a detector for wireless apparatus, 105 the combination with a fixed crystal, of a movable arm, a contact wire carried thereby for contact with the fixed crystal, means whereby a crystal may be removably secured to the arm and means included in the securing means to provide a housing for 110 the contact wire.

2. In a detector for wireless apparatus, 110 the combination with a fixed crystal, of a

movable arm; a longitudinally movable contact wire extending from one end of the arm for contact with the crystal, means for yieldingly forcing the contact wire outward, 5 means whereby a crystal may be removably secured to the arm and means included in the securing means whereby the contact wire will be forced inwardly within the arm.

3. In a detector for wireless apparatus, 10 the combination with a fixed crystal, of a

movable arm, a contact wire carried thereby for contact with the fixed crystal, a second crystal and combined means including a sleeve having a threaded engagement with one end of the arm for removably securing the said second crystal to the arm for contact with the fixed crystal and to provide a housing for the contact wire.

In testimony whereof I affix my signature.

FRED WEINBERG.
